UNITED STATES PATENT OFFICE

156,768

BRASSIÈRE

Charles M. Sachs, West Newton, Mass., assignor to Formaid Co., Boston, Mass., a corporation of Massachusetts

Application November 20, 1948, Serial No. 149,740

Term of patent 14 years

(Cl. D20—4)

To all whom it may concern:

Be it known that I, Charles M. Sachs, a citizen of the United States of America, residing at West Newton, in the county of Middlesex and Commonwealth of Massachusetts, have invented a new, original, and ornamental Design for a Brassière, of which the following is a specification, reference being had to the accompanying drawing, forming part thereof.

Fig. 1 is a front view of a brassière, showing my new design;

Fig. 2 is a rear view thereof;

Fig. 3 is a side view looking to the left of Fig. 1; and

Figs. 4 and 5 are enlarged sections taken on lines 4—4 and 5—5 respectively of Fig. 1.

I claim:

The ornamental design for a brassière, as shown.

CHARLES M. SACHS.
